LINOLEUM OR SIMILAR ARTICLE

George W. Johnson, San Francisco, Calif., assignor to Pabco Products Inc., San Francisco, Calif., a corporation of Delaware

Application February 1, 1954, Serial No. 28,763

Term of patent 7 years

(Cl. D92—17)

The drawing is a plan view of a piece of linoleum showing my design. On such drawing, the broken lines outline a design unit which is repeated in regular succession as indicated by the extensions beyond the boundaries of such unit.

I claim:

The ornamental design for a linoleum or similar article, substantially as shown and described.
